UNITED STATES PATENT OFFICE.

DAVID ATHERTON, OF PHILIPSBURG, PENNSYLVANIA.

PAVING-BLOCK.

933,521.

Specification of Letters' Patent.

Patented Sept. 7, 1909.

Application filed November 8, 1908. Serial No. 460,810.

To all whom it may concern:

Be it known that I, DAVID ATHERTON, a citizen of the United States, and a resident of Philipsburg, in the county of Center and State of Pennsylvania, have invented a new and Improved Paving-Block, of which the following is a full, clear, and exact description.

The object of the invention is to provide a new and improved paving block, of which a series can be conveniently assembled to interlock with each other and to form transverse interlocking courses or rows, with a view to prevent transverse shifting of the blocks in the roadway even if the roadway is without curbs.

The invention consists of novel features and parts and combinations of the same, which will be more fully described herein-after and then pointed out in the claims.

A practical embodiment of the invention is represented in the accompanying drawings forming a part of this specification, in which similar characters of reference indicate corresponding parts in all the views.

Figure 1 is a plan view of the improvement, showing a number of courses of blocks forming the roadway; Fig. 2 is an enlarged perspective view of one of the blocks; and Fig. 3 is a vertical section of the same on the line 3—3 of Fig. 2.

The paving blocks A for forming the roadway, are alike in construction and are arranged in transverse courses in such a manner that the blocks in successive courses break joints, and the joints of all the courses extend in a zigzag line transversely of the road bed, as indicated in Fig. 1. In order to accomplish this result, each block A has both sides A', A² made V-shape, so that the half of the side of a block in one course fits a corresponding half of a block in the adjacent course, whereby the blocks in adjacent courses are securely interlocked to prevent shifting in a transverse direction of the roadway.

The halves of a V-shaped side A' of each block are provided with vertically disposed

spacing ribs A³, A⁴, preferably located about midway of each half, as plainly indicated in Figs. 1 and 2, the ribs A³, A⁴ of the blocks, in one course abutting against the non-ribbed V-shaped sides A² of the blocks in an adjacent course, so that sufficient space is formed between adjacent courses for the reception of grouting or other binding material.

From the foregoing it will be seen that by constructing the block in the manner described, the blocks in successive courses interlock with each other, and all the courses are interlocked, to prevent shifting in a transverse direction of the blocks in the roadway.

Having thus described my invention I claim as new and desire to secure by Letters Patent:

1. A roadway comprising transverse courses of paving blocks, each block having both faces V-shaped, and successive courses breaking joints, one-half of the side of a block in one course fitting a corresponding half of the block in the adjacent row, and vertical spacing ribs on the halves of one side of a block in one course abutting against the smooth halves of adjacent blocks in the next course.

2. A roadway comprising transverse courses of paving blocks, each block having both faces V-shaped, and successive courses breaking joints, one-half of the side of a block in one course fitting a corresponding half of a block in the adjacent row, vertical spacing ribs on the halves of one side of a block in one course abutting against the smooth halves of the adjacent blocks in the next course, and a grouting material between the joints of successive courses.

In testimony whereof I have signed my name to this specification in the presence of two subscribing witnesses.

DAVID ATHERTON.
